UNITED STATES PATENT OFFICE.

OLIVER C. HACKETT AND CHARLES W. HACKETT, OF AKRON, OHIO.

DESIGN FOR AN ERASER.

SPECIFICATION forming part of Design No. 25,137, dated February 11, 1896.

Application filed December 19, 1895, Serial No. 572,720. Term of patent 7 years.

To all whom it may concern:

Be it known that we, OLIVER C. HACKETT and CHARLES W. HACKETT, of Akron, in the county of Summit and State of Ohio, have invented and produced a new and original Design for an Eraser, of which the following is a full, clear, and exact description.

Reference is to be had to the accompanying drawings, forming a part of this specification, in which similar characters of reference indicate corresponding parts in both the figures.

Figure 1 is a perspective view of an eraser embodying our new design; and Fig. 2 is a cross-section on line 2 2, Fig. 1.

The leading feature of our design consists in an eraser the head *a* of which is approximately oval in cross-section at about its center and tapers toward both ends, presenting

an elongated flattened ovate form, said head having on one side a roughened surface and 20 a smooth surface on the opposite side, and merging into the shank *b*.

In detail the shank *b* is round, is contracted or of reduced thickness adjacent to the head, and is elongated. Further, the shank is gradually enlarged toward the rear and merges into the angular handle end *c*.

We claim—

The design for an eraser herein shown and described.

OLIVER C. HACKETT.
CHARLES W. HACKETT.
